ATTORNEY

UNITED STATES PATENT OFFICE

RICHARD D. WEARNE, OF GARY, INDIANA

SELECTIVE LUBRICANT DISTRIBUTOR

Application filed March 30, 1929. Serial No. 351,442.

This invention relates to improvements in selective lubricant distributors. One important object of the invention is to provide a device having a multi-port control whereby the device can be adjusted or manipulated to distribute predetermined amounts of lubricant under pressure to different machines consecutively or to a selected machine only.

A further object of the invention is to provide a novel and simple construction of distributor which is capable of ready installation and which is thoroughly efficient and practical in use.

With the foregoing and other objects in view, which will appear as the description proceeds, the invention resides in the combination and arrangements of parts and in the details of construction hereinafter described and claimed, it being understood that changes in the precise embodiment of the invention herein disclosed can be made within the scope of what is claimed without departing from the spirit of the invention.

In the accompanying drawings:—

Figure 1 is a longitudinal sectional view taken through the distributor, the body of the same being foreshortened.

Figure 2 is a top plan view of the main casing of the distributor with the operating handles removed.

Figure 3 is an elevation of the handle-carrying end of the distributor, portions of the operating handles being shown as broken off.

Figure 4 is a diagrammatic sectional view taken through one of the distributing tubular members showing the relative position of the ports therein for controlling distribution.

Figure 5 is a section on line 5—5 of Figure 2 with the distributing ports disaligned.

Figure 6 is a view similar to Figure 5 showing two of the distributing ports alined with one of the outlet ports of the main casing, the view being taken on line 5—5 of Figure 2.

Referring to the drawings, the numerals 7 designate supports for a main casing 8 of the present distributor which, as illustrated, is provided with a longitudinal cylindrical bore 8' and with a plurality of diametrically disposed outlet ports 9 communicating with the longitudinal bore 8', each of the ports being

provided with pipe connecting threads 10 adjacent the upper face of the main casing.

A removable plug or cap 12 is fitted in one end of the main casing, while at the opposite end is a fixed dial 13 having a rim 14 provided with a plurality of recesses 15 adjacent each dial number.

A tubular member 16 is mounted within the bore of the main casing and terminates short of the cap 12 to provide an inlet chamber 17 which communicates with an inlet connection 18 of the main casing so that lubricant under pressure may be supplied to said chamber 17. A reduced end 19 of the tubular member 16 projects exteriorly of the main casing and is packed, as at 20, so that a retaining ring 11 which threadedly engages the main casing and holds the parts in position, will also prevent longitudinal movement of the tubular member.

Fitted upon the outer extremity of the reduced end 19 is a disk 21 having a lug 21' which functions as a key for coupling the same with the tubular member 16 for unitary rotation. Said disk has formed integral therewith an indicating member or pointer 22 and an operating handle 22', the latter being constructed in two sections connected by a hinge 25 so that the outer section 24 may yield but be held in normally alined position by means of a spring 23. The outer section is provided with a locking recess 27, the purpose of which will presently appear, and with a lug 26 which latter normally engages one of the recesses 15 to lock the handle 22' against rotation and at the selected point upon the dial 13.

An inner sleeve or tubular member 28 fits telescopically the tubular member 16 and a sealing member 29 threadedly engages the inner open end of the sleeve 28 and has a tubular projection 30 disposed in the chamber C of the member 28. Ports 31 are formed in the member 29 and communicate with the chamber 17 so that the lubricant is directed therethrough into the hollow portion 32 of the sealing member 29 and, as will later appear, into the chamber C. Mounted within the cap 12 and located within the hollow portion 32 of the member 29, is a cylindrical

plunger 33 equipped with a gasket 34. This plunger is threaded, as at 36, to internal threads 37 of the cap 12 so that upon manipulation of a hand-wheel 38 on the plunger the pressure upon the plunger regulated accordingly.

A port 39 is provided within the chamber 32 and is controlled by ball valve 40, engaged by a spring 41 exerting a pressure upon said ball to hold it upon its seat. Said spring 41 is retained in place by means of a pin 42. A port 43 is provided through the wall of projection 30 beyond the port 39 so that the lubricant is supplied into the chamber C.

Attached to the manipulating end 44 of the inner tube 28 by means of a screw 46 is a handle 47 which is provided with a locking pin 48 to engage the opening 27 of the section 24 of the handle 22', the purpose of which will presently appear. Also carried by the handle at the opposite side thereof is a pointer 49 for cooperating with the zero indication 45 of the dial 21.

The tubular member 28 is provided with a plurality of spirally arranged ports 50, as illustrated diagrammatically in Figure 2, and upon substantially the upper 180° or half of the circumference of said member, while formed in the outer sleeve or tubular member 16 is a similar number of ports 51, said ports 50 and 51, when alined, as illustrated in Figure 6, communicating with their respective outlet ports 9 so that lubricant from the chamber C will be distributed to such selected outlet port.

The ports 51 in the sleeve 16 are also arranged spirally, and will assume the various numbered positions illustrated so as to correspond with the dial numbers upon the dial 18, indicating at a glance by the position of the pointer 22 the positions of the respective ports 51 with relation to the outlet ports 9.

In the present construction, when the levers or handles 22' and 47 are interlocked or connected at openings 27 and pin 48, the ports 50 and 51 of the respective sleeves are in registry. In this condition, starting at zero and turning the said handles unitarily in a clockwise direction, will effect the discharge of lubricant therethrough and through the outlet ports 10 consecutively.

Should discharge of lubricant through any individual port 10 to the exclusion of the other ports 10 be desired, the handles or levers are first moved to neutral positions as indicated by their pointers. Then with such levers disengaged at 27-48, lever 22' is turned to the desired port as indicated by pointer 22 on the dial 14 and lever 47 is turned until pointer 49 coincides with zero mark 45 which will align the desired ports.

It is also apparent from the arrangement and construction of the pump plunger that the pressure may be increased and thus assist in forcing the same into the chamber C after

having been admitted into the hollow portion 32.

I claim:

1. A selective lubricant distributor, including a main casing having a longitudinal bore and provide with an inlet port and a plurality of outlet ports, two concentric rotary tubular members fitting in said bore and provided with distributing ports for relative alinement with one another and the respective outlet ports of the main casing, independent means carried by each member to permit independent adjustment of said members, and means for locking said means for simultaneous manipulation of both members. 70

75

2. A selective lubricant distributor, including a main casing having a longitudinal bore and provided with an inlet port and a plurality of outlet ports, two concentric rotary tubular members fitting in said bore and provided with distributing ports for relative alinement with one another and the respective outlet ports of the main casing, independent means carried by each member to permit independent adjustment of said members, 80

85

means for locking said means for simultaneous manipulation of both members, means for sealing the inner end of the innermost concentric member and forming a lubricant-communicating means between the inlet port and the interior of said sealing means. 90

95

3. A selective lubricant distributor, including a main casing having a longitudinal bore and provided with an inlet port and a plurality of outlet ports, two concentric rotary tubular members fitting in said bore and provided with distributing ports for relative alinement with one another and the respective outlet ports of the main casing, independent means carried by each member to permit independent adjustment of said members, means for locking said means for simultaneous manipulation of both members, means for sealing the inner end of the innermost concentric member and forming a lubricant-communicating means between the inlet port and the interior of said sealing means, 100

105

means for sealing the inner end of the innermost concentric member and forming a lubricant-communicating means between the inlet port and the interior of said sealing means, said latter means being provided with a valve controlled port and a pump bore communicating therewith, and a piston mounted in said bore and operable exteriorly of the main casing. 110

115

4. A selective lubricant distributor, including a main casing having a longitudinal bore and provided with an inlet port and a plurality of outlet ports, two concentric rotary tubular members fitting in said bore and provided with distributing ports for relative alinement with one another and the respective outlet ports of the main casing, independent means carried by each member to permit independent adjustment of said members, means for locking said means for simultaneous manipulation of both members, means for sealing the inner end of the innermost concentric member and forming a lubricant-communicating means between the inlet port and the interior of said sealing means, 120

125

means for sealing the inner end of the innermost concentric member and forming a lubricant-communicating means between the inlet port and the interior of said sealing means, 130

- tric member and forming a lubricant-communicating means between the inlet port and the interior of said sealing means, said latter means being provided with a valve controlled 5 port and a pump bore communicating therewith, and a piston mounted in said bore and operable exteriorly of the main casing, and at the end opposite to the said independent means.
- 10 5. A selective lubricant distributor, including a main casing having a longitudinal bore and provided with an inlet port and a plurality of outlet ports, two concentric rotary tubular members fitting in said bore and provided with distributing ports for relative alinement with one another and the respective outlet ports of the main casing, independent means carried by each member to permit independent adjustment of said members, and means for locking said means for simultaneous manipulation of both members, the ports of the concentric members being arranged spirally throughout the length of the members and for alinement with the respective outlet ports one at a time. 25
6. A selective lubricant distributor, including a main casing having a longitudinal bore and provided with an inlet port and a plurality of outlet ports, two concentric rotary tubular members fitting in said bore and provided with distributing ports for relative alinement with one another and the respective outlet ports of the main casing, independent means carried by each member to permit independent adjustment of said members, means for locking said means for simultaneous manipulation of both members, said concentric members being of lesser length than the bore and providing a chamber at one 30 end of the main casing and in communication with the inlet port, and a sealing member of tubular form fitting into the inner end of the inner concentric member and provided with ports leading from the said chamber to the interior of the sealing member, said sealing member being provided with a port communicating with the bore of the inner concentric member, said sealing member having its bore open toward the opposite end of the main casing to the operating means and being provided with a valve seat, a spring seated valve mounted in the sealing member and controlling said valve seat, a cap sealing member for the main casing and inlet chamber, and a manually operable pump plunger mounted in the cap and the bore of the tubular sealing member and operable exteriorly of the main casing. 35
- 40 7. A selective lubricant distributor, including a main casing having a longitudinal bore and provided with an inlet port and a plurality of outlet ports, two concentric rotary tubular members fitting in said bore and provided with distributing ports for relative alinement with one another and the respective outlet ports of the main casing, independent means carried by each member to permit independent adjustment of said members, means for locking said means for simultaneous manipulation of both members, said concentric members being shorter than the bore and providing a chamber at one end of the main casing and in communication with the inlet port, a sealing member of tubular form fitting into the inner end of the 45 50 55 60 65 70 75 80 85 90 95 100 105 110 115 120 125 130
- inner concentric member and provided with ports leading from the said chamber to the interior of the sealing member, said sealing member being provided with a port communicating with the bore of the inner concentric member, said sealing member having its bore open toward the opposite end of the main casing to the operating means and being provided with a valve seat, a spring seated valve mounted in the sealing member and controlling said valve seat, and a cap sealing member for the main casing and inlet chamber.
8. A selective lubricant distributor, including a main casing having a longitudinal bore and provided with an inlet port and a plurality of outlet ports, two concentric rotary tubular members fitting in said bore and provided with distributing ports for relative alinement with one another and the respective outlet ports of the main casing, independent means carried by each member to permit independent adjustment of said members, means for locking said means for simultaneous manipulation of both members, said concentric members being of lesser length than the bore and providing a chamber at one end of the main casing and in communication with the inlet port, a sealing member of tubular form fitting into the inner end of the inner concentric member and provided with ports leading from the said chamber to the interior of the sealing member, said sealing member being provided with a port communicating with the bore of the inner concentric member, said sealing member having its bore open toward the opposite end of the main casing to the operating means and being provided with a valve seat, a spring seated valve mounted in the sealing member and controlling said valve seat, a cap sealing member for the main casing and inlet chamber, and a manually operable pump plunger mounted in the cap and the bore of the tubular sealing member and operable exteriorly of the main casing.
- In testimony whereof I have hereunto set my hand.
- RICHARD D. WEARNE.
